UNITED STATES PATENT OFFICE.

WILLIAM N. BLACKBURN, OF DREXEL HILL, PENNSYLVANIA.

FLUE-WALL FACING.

Application filed May 31, 1924. Serial No. 717,122.

To all whom it may concern:

Be it known that I, WILLIAM N. BLACKBURN, a citizen of the United States, residing at Drexel Hill, in the county of Delaware and State of Pennsylvania, have invented certain new and useful Improvements in Flue-Wall Facings, of which the following is a specification, reference being had to the accompanying drawings.

10 Flue walls leading from a fireplace are more or less rough and irregular, particularly as regards the sloping or inclined parts of the flue wall which lead to the chimney thereof, and this is true even when the flue walls are constructed of concrete or material other than brick. As a consequence, the passage of the smoke or products of combustion is more or less retarded.

20 The purpose of the present invention is to improve upon the construction which is illustrated in my patent on flue wall facings, #1,436,750, granted on November 28, 1922.

25 One of the objects of the present invention is to provide a flue wall facing or lining plate having laterally projecting lugs, as illustrated in my prior patent, these lugs being so disposed, however, that they are vertical and will, therefore, fit within the vertical joints of the brick work.

30 Another object is to provide a construction of this character wherein the lateral flanges or lugs are so formed as to provide shoulders which materially assist in supporting the brick work of the chimney, and 35 which are also so designed as to support a base for a flue lining, this base being furthermore so constructed as to lock the lower end of the flue lining in place and prevent any tendency of the flue lining to get out of 40 alignment with the base.

Other objects will appear in the course of the following description.

My invention is illustrated in the accompanying drawings, wherein:—

45 Figure 1 is a front elevation of a chimney, the front wall of which is broken away to show the flue and the position of my improved facing plates therein;

50 Figure 2 is a vertical sectional view on the line 2—2 of Figure 1;

Figure 3 is a perspective view of the opposed facing plates;

Figure 4 is a vertical sectional view on the line 4—4 of Figure 5;

55 Figure 5 is a top plan view of the base for the chimney lining;

Figure 6 is a perspective view of one of the bolts used for bolting the upper ends of the facing plates in place;

Figure 7 is a perspective view of a modified form of the flue lining;

Figure 8 is a perspective view of the frame which supports the damper;

Figure 9 is a fragmentary sectional view on the line 9—9 of Figure 3;

In the drawings, 1 designates the chimney generally, 2 the fire place, and 3 the smoke flue which leads upward from the back of the fire place and which communicates with the vertical and relatively small flue 6 of the chimney. The flue 3 has vertical walls at its lower portion and upwardly and inwardly extending walls above these vertical walls which are directed toward the chimney throat. There are two of these sloping or inclined walls on each side of the chimney.

In order to cover up the irregularities which usually occur in these walls, I provide flue facing plates or linings 7 which are disposed upon the inner faces of the inclined or sloping walls of the flue. These plates may be of cast iron, terra cotta or any other suitable material. Each facing plate is provided with a marginal reinforcement or thickened portion 8, and projecting laterally from the opposite longitudinal edges thereof are the lower lugs 9 and the upper lugs 10. The lugs 9 are disposed somewhat above the extreme lower edge of the plate 7. These lugs, as shown in Figure 3, are disposed in a normally vertical position, that is when the plates are disposed within the throat of the chimney these lugs are vertical and, therefore, are parallel to the vertical joints between the bricks of the chimney. Furthermore, the upper and under faces of these lugs provide shoulders which support the brick work of the chimney. The upper lugs 10 are intended to be disposed practically on a level with the bottom of the chimney throat.

From the upper margin of the plate extends the upwardly projecting lugs. These lugs are also vertical and there are preferably a pair of these lugs, the material of the plate being thickened immediately below these lugs 11 and behind the rib or reinforce 105 8 so as to form shoulder portions 13 which have bolt apertures 14. Through these apertures pass the transversely extending bolts 15, one of which is illustrated in Figure 6, each of these bolts being screw-threaded at 110

its opposite ends and carrying at each end a pair of nuts 16, between which each plate 7 is adapted to be engaged. It will be noted that the inner face of the plate 7 is perfectly smooth and unbroken and that the inner faces of the lugs 11 are flush with the upper end of this smooth unbroken face of the plate.

Coacting with the lugs 11 and supporting 10 the lining 17 of the chimney is a base 18 which is formed of metal, terra cotta, or any other suitable material, this base being angular in cross section so as to provide an upwardly extending portion 19 which, as 15 illustrated, is annular in form. The flat base plate from which this annular portion extends is formed on its margins with recesses 20 so formed as to receive the upwardly extending lugs 11 and interlock therewith, the 20 opposite margins of this base 18 resting upon the upper edges of the plates. The inner faces of the annular portion 19 of this base 18 are formed with upwardly extending ribs 21 which project beyond the upper edge of 25 the annular portion 19 so as to overlap the lower ends of the terra cotta flue lining 17 and thereby interlock this flue lining with the base.

In Figure 7, I have illustrated a construction 30 wherein the laterally projecting lugs 9 and 10 are dispensed with, but otherwise than this the construction of the plate 7^a is exactly the same as the plate 7. In Figure 8 is illustrated the damper which is used in 35 connection with the fire place, this damper comprising a frame 22 having a damper plate 23 hinged thereto, this damper plate being held in any adjusted position by a rack 24.

40 It will be seen from Figure 3 that if the plates 7 are used with a relatively large flue lining or chimney lining 17 that this chimney lining, if it is rectangular in form, will rest upon the shoulders formed at the upper ends 45 of the thickened portions 13 but, of course, these shoulders act to otherwise support the brick work.

It will be seen that the flue wall lining or facing plates have no flanges on the inner 50 faces thereof and that they do not in any way show and do not in any way extend to the front wall of the fire place. While preferably the bolts 15 will be used, I do not wish to be limited to this.

55 While in these drawings I have illustrated a flue cap 18, as shown in Figure 4, of terra cotta which is adapted to support a circular flue 17 and which coacts with the plate 7, I do not wish to be limited to this, as a square 60 terra cotta flue or flue of other material rectangular in cross section might be used in place of this circular flue 17, as is illustrated in my prior Patent #1,436,750, granted November 28, 1922, so that the flue 65 construction is adapted either for use with

a circular flue or with a square flue, as desired. Of course, where a square flue is used, as was shown in my prior patent, it extends outward of the lugs 11 and rests upon the shoulders 13.

70 It will be seen that this construction ties in the terra cotta flue and acts as a foundation for the same and the angular lugs tie in the front and back walls, enabling a perfect bond to be made and increasing the 75 strength of the construction. The two tie bolts 15 are provided at each end with a sufficient thread for adjustment and each end of the tie bolt is fitted with two nuts for locking the flue throat in position. One 80 of the important features which this flue throat possesses is that it permits the mason to carry back the lower construction of the front of the fireplace at the proper angle, placing the flue in proper alignment and 85 relation to the fireplace. This is for the reason that, as illustrated in Figure 2, the forward edge of the plate 7 (and the same 90 applies equally well to the plate 7^a shown in Figure 7) is upwardly and inwardly inclined, thus permitting the carrying back of the front wall construction to form the 95 throat of the fireplace. These plates 7 and 7^a are formed of standard lengths having a 100 length equal to the height of so many bricks as, for instance, nine bricks, as shown in Figure 1, so that the tenth brick will form a sealing joint with the top of the plate. It is to be particularly noted that the 105 apertures 14 are elongated and that the bolts 15 pass through these plates 7 at the upper 110 ends thereof instead of, as shown in my prior patent, passing through the plates 7 below the upper end thereof.

This construction permits the lower ends 115 of the plates 7 to be set further out or nearer together to thereby suit any circumstances of work or irregularities in the framework without changing the area defined between the upper ends of the plates. In my construction, furthermore, the nuts 16 on the 120 bolts 15 fit flat against the outer faces of the portions 13, whereas in my prior patent the bolts did not fit against the inclined faces of the flue plates but only bore at one 125 edge against these inclined faces. With my construction either a square flue lining or a round flue lining may be used as desired without in any way, in case a round flue lining is used, diminishing the area of the 130 passage through the flue lining and yet at the same time giving full support to the flue lining.

I claim:—

1. In a flue, a pair of flue wall facing plates disposed in upwardly convergent relation, each plate having upwardly projecting lugs disposed at an obtuse angle to the plane of the facing plate, and a flue supporting base having a horizontal plate

recessed to accommodate these lugs, the opposite margins of the base resting upon the upper edges of said plates.

2. In a flue, a pair of upwardly convergent flue wall facing plates each having upwardly projecting lugs disposed at an obtuse angle to the plane of the facing plate, and a flue supporting base having a horizontal plate recessed to accommodate these lugs, the opposite margins of the base resting upon the upper edges of said plates, the base having an upwardly projecting wall adapted to abut against the lower edge of the flue lining and having upwardly projecting ribs upon the inner face of the wall extending beyond the wall and adapted to overlap the flue lining.

3. As an article of manufacture, a flue wall facing plate, the plate being formed with laterally projecting ears disposed adjacent the lower and upper ends of the plate, these ears being disposed at an obtuse angle to the plate whereby when said plate is disposed within the inclined portion of a flue 25 said ears will be disposed in vertical planes.

4. As an article of manufacture, a flue wall facing plate, the plate being formed with laterally projecting ears disposed adjacent the lower and upper ends of the plate, 30 these ears being disposed at an obtuse angle to the plate whereby when said plate is disposed within the inclined portion of a flue said ears will be disposed in vertical planes, the upper margin of the plate having a plurality of upwardly projecting lugs disposed in a vertical plane.

5. As an article of manufacture, a flue wall facing plate, the plate being formed with laterally projecting ears disposed adjacent the lower and upper ends of the plate, 40 these ears being disposed at an obtuse angle to the plate whereby when said plate is disposed within the inclined portion of a flue said ears will be disposed in vertical planes, the upper margin of the plate having a plurality of upwardly projecting lugs disposed in a vertical plane, the margin of

the plate being reinforced upon its outer face and the upper end of the plate behind the reinforced margin being thickened immediately below each of said upwardly extending lugs, the thickened portion having transversely extending perforations for the passage of bolts.

6. As an article of manufacture, a base 55 for flue linings comprising a member angular in cross section to provide a flat horizontal portion and an upwardly extending wall, the inner face of the wall being provided with lugs extending beyond the upper 60 edge of the wall to thereby engage the flue lining and lock it in place.

7. As an article of manufacture, a pair of flue wall facing plates having obtusely angled portions at their upper ends, the 65 facing plates being adapted to be disposed at an angle to a vertical plane with the angled portions in a vertical plane, the angled portions being formed with transversely extending passages at right angles to the 70 angled portions, and bolts passing through said passages.

8. As an article of manufacture, a flue wall facing plate formed with laterally projecting anchoring ears disposed adjacent the 75 lower and upper ends of the plate and with vertically extending ears at the upper end of the plate, one edge of the plate extending upward and inward relative to the opposite edge of the plate.

9. In a chimney having an upwardly directed flue opening and a vertically extending throat disposed at the upper end of the flue opening, oppositely disposed facing plates disposed against the opposite inclined 85 faces of the flue, and bolts connecting the upper ends of said facing plates, the facing plates having vertically elongated openings through which said bolts pass permitting the plates to be swung relative to the bolts.

In testimony whereof I hereunto affix my signature.

WILLIAM N. BLACKBURN.
